Primary Examiner — Thomas Johannes*Assistant Examiner* — Leanne Thomas(74) *Attorney, Agent, or Firm* — Blue Filament Law PLLC; Avery N. Goldstein(57) **CLAIM**

The ornamental design for a container lid, as shown and described.

DESCRIPTION

FIG. 1 is an elevated front perspective view of a container lid with a popcorn bucket shown in ghost for context, the bucket not being part of the container lid;

FIG. 2 is a top view of the container lid depicted in FIG. 1; FIG. 3 is a front view of the container lid depicted in FIG. 1; FIG. 4 is a back view of the container lid depicted in FIG. 1; FIG. 5 is a side view of the container lid depicted in FIG. 1; FIG. 6 is an opposing side view of the container lid depicted in FIG. 1 relative to the side view depicted in FIG. 5; and, FIG. 7 is a bottom view of the container lid depicted in FIG. 1.

The broken line alphanumeric characters illustrate portions of the container lid which form no part of the claimed design.
